UNITED STATES PATENT OFFICE.

WILLIAM H. MARGERISON AND ALBERT E. MARGERISON, OF PHILADELPHIA, PENNSYLVANIA.

TERRY FABRIC.

Application filed February 24, 1926. Serial No. 90,355.

The invention relates to certain new and useful improvements in terry fabrics and more particularly to a form of weave for fabrics of this character employed as towels and the like, to produce materially increased strength, durability and wearing qualities, said effects resulting from the particular disposition of the bottom warps, loop warps, binder warps and the weft threads, as illustrated in the accompanying drawing which shows the weave in diagram.

Referring to the drawing, A indicates a first loop warp and B a second loop warp, the first being formed on the back of the fabric and the second on the face of the fabric.

Disposed between each pair of loop warps A and B is a pair of bottom warp threads C and D, which are drawn or woven as a single thread, and disposed between each pair of loop warps B and A is a binder warp E. This arrangement and disposition of loop warps, bottom warps in pairs and single binder warps E is repeated in the order stated throughout the fabric structure.

Interwoven with the loop warps A and B, the pairs of bottom warps C and D and the binder warps E is a weft thread 1, and disposed between and within the loops of the warps A and B and interwoven with the pairs of bottom warps C and D and the binder warps E are two weft threads 2 and 3, this particular disposition of the weft threads 1, 2 and 3 being repeated throughout the fabric.

The particular disposition and arrangement of the double warp threads C and D,

which are woven as a single thread, and the interwoven weft threads 2 and 3 produce an exceptionally strong base or foundation fabric, which is materially reinforced by the weft thread 1 and the binder warp E, which are effective in locking the loop warps securely in position, while the disposition of the loops in close order and sequence insures a thick, dense and uniform pile that is particularly effective in the manufacture of towels and similar articles.

What we claim is:

1. A terry fabric comprising bottom warps; binder warps; and loop warps, disposed in the order of a first loop warp, a pair of bottom warps drawn as one, a second loop warp and a binder warp, in regular repetition; a weft thread interwoven with the loop warps, the pair of bottom warps and the binder warp, and two weft threads interwoven with the pair of bottom warps and the binder warp, in regular repetition.

2. A terry fabric comprising bottom warps; binder warps; and loop warps, disposed in the order of a first loop warp on the back of the fabric, a pair of bottom warps drawn as one, a second loop warp on the face of the fabric and a binder warp, in regular repetition; a weft thread interwoven with the loop warps, the pair of bottom warps and the binder warp, and two weft threads interwoven with the pair of bottom warps and the binder warp, in regular repetition.

In testimony whereof we affix our signatures.

WILLIAM H. MARGERISON.
ALBERT E. MARGERISON.
